(57) **CLAIM**

The ornamental design of a server module for a computer system, as shown and described.

DESCRIPTION

FIG. 1 is a left, front isometric view of a server module for a computer system, showing our new design;

FIG. 2 is a right, front isometric view thereof;

FIG. 3 is an enlarged handle view thereof;

FIG. 4 is a front view thereof;

FIG. 5 is a left view thereof;

FIG. 6 is a right view thereof; and,

FIG. 7 is a top view thereof.

In FIG. 3, the inside surface of the handle is hatched to show the color blue. The appearance of the server module as seen from the rear and the bottom forms no part of the claimed design.
